UNITED STATES PATENT OFFICE.

FRANK S. SCOTT, OF HEYBURN, IDAHO.

SHOE-SHINING STAND.

1,388,768.

Specification of Letters Patent. Patented Aug. 23, 1921.

Application filed April 7, 1920. Serial No. 372,052.

To all whom it may concern:

Be it known that I, FRANK S. SCOTT, a citizen of the United States of America, residing at Heyburn, in the county of Minidoka and State of Idaho, have invented new and useful Improvements in Shoe-Shining Stands, of which the following is a specification.

The object of the invention is to provide an apparatus for use in shoe shining operations whereby a number of customers may be simultaneously and consecutively served under conditions which provide for the progressive disposal thereof to economize time and space and avoid congestion and confusion as to the precedence of customers or the order in which they shall be accepted for receiving the contemplated attention; and also to improve the construction of devices of this general type to increase the convenience of the customers while their shoes are receiving attention; and with these objects in view the invention consists in a construction and combination of parts of which a preferred embodiment is shown in the accompanying drawings, wherein:

Figure 1 is a plan view of the apparatus.

Fig. 2 is a central sectional view of the same.

Fig. 3 is a detail view of one of the inside foot rests and the means whereby the same is mounted.

The device consists essentially of a revolvable table or platform 10 arranged in convenient relation with the floor 11 or other equivalent supporting surface to the end that customers may readily step from the latter to the former, and outer and inner annular or concentric series of seats 12 and 13 supported by the table or platform and separated by the interposed annular back 14, both seats and back preferably being provided with suitable upholstery as shown respectively at 15 and 16, and the upholstery 45 for the back preferably consisting of a cushion foldable at its longitudinal center as shown at 17 to fold over and hang upon the upper edge of the back so as to serve for both the inner and outer series of seats.

At suitable intervals upon corresponding concentric outer and inner foot ledges 18 and 19 are arranged sets of shoe shining foot rests 20 and 21 to the end that a number of customers may be simultaneously served both exteriorly and interiorly of the series of

seats, the purpose being to have the interior series of seats reserved for ladies, and access being given to the inner circle through a gateway represented by the space 22 as shown in Fig. 1.

Also preferably the foot rests 21 of the inner series have their shanks 23 carried by slides or travelers 24 mounted in guides 25 disposed radially of the table or platform to the end that the rests may be moved outwardly into practical contact with the riser 26 between the foot ledge 19 and the inner seat, out of the way of the skirts of customers in mounting or dismounting from the seat.

It is the purpose to provide for approaching the table or platform for attention in a column or series to avoid confusion, congestion or crowding and to progressively move the platform while the customer is being served to the end that departure from the same may occur so far as possible in a like sequence or consecutive order, and therefore the table or platform is preferably mounted for a slow revoluble movement by providing it with depending bearing rails 27 arranged in coöperative relation with track rails 28 of which anti-friction balls or rollers 29 may be disposed, and to connect with the table or platform as at a central point a drive shaft 30 with which any suitable driving power may be connected such as a motor 31 with suitable interposed gearing or transmission mechanism indicated at 32.

By this arrangement, for example, the customers may step upon the platform in order or sequence as the empty seats are presented and may leave the same in substantially the same order at a prescribed station in the course of progress of the table or platform, the shoe shining operation being conducted while the passenger is in transit from the loading point to the discharging point, and the speed of rotation of the table or platform being regulated to give sufficient time under ordinary circumstances for affording the necessary opportunity to the attendants to complete the desired service.

What I claim is:

1. A shoe shining stand having a revolvable table or platform, seats and foot rests disposed in concentric series thereon and means for communicating rotary motion to the table or platform.

2. A shoe shining stand having a revolvable

table or platform, concentric inwardly and outwardly facing seats supported by the platform, corresponding series of foot rests disposed in operative relation with said series of seats, and means for communicating progressive movement to the table or platform.

3. A shoe shining stand having a revoluble table or platform, concentric inwardly and outwardly facing seats supported by the platform, corresponding inner and outer series of foot rests disposed in operative relation with said series of seats, the foot rests of one series being mounted for radial folding movement with relation to the corre-

sponding seats, and means for communicating rotary motion to the table or platform.

4. A shoe shining stand having a revoluble table or platform, concentric inner and outer series of seats and related foot ledges supported by the table or platform and interrupted to afford an entrance gate to the inner series of seats, inner and outer series of foot rests carried by the foot ledges in operative relation with said series of seats, and means for communicating rotary motion to the table or platform.

In testimony whereof I affix my signature.

FRANK S. SCOTT.
